UNITED STATES PATENT OFFICE.

ALICE E. BOOTH, OF LOGANSPORT, INDIANA.

WORK-HOLDER.

No. 856,022.

Specification of Letters Patent.

Patented June 4, 1907.

Application filed October 9, 1905. Serial No. 281,994.

To all whom it may concern:

Be it known that I, ALICE E. BOOTH, a citizen of the United States, residing at Logansport, in the county of Cass and State of Indiana, have invented certain new and useful Improvements in Work-Holders, of which the following is a specification.

My invention has reference to devices for holding textile fabric while the same is being sewed or otherwise operated on; and it has for one of its objects to provide a device adapted to be clamped or otherwise fixed on a table top or other support, and constructed in such manner that textile fabric may be readily engaged with and disengaged from it without any injury whatever to the fabric, and yet there is no liability of the fabric being casually released when the same is manipulated incident to sewing, basting or ripping thereof.

Another object of the invention is the provision of a device for the purpose stated, embodying such a construction that an ordinary needle or pin may be utilized for engaging the fabric to be held, and when the said needle or pin is broken, bent or otherwise impaired, it may be quickly and easily removed and as readily replaced with a new needle or pin.

Other advantageous features peculiar to my invention will be fully appreciated from the following description when the same is considered in connection with the accompanying drawings, forming part of this specification, in which:

Figure 1 is a perspective view illustrating the manner in which the device constituting the present and preferred embodiment of my invention is fixed on a table top and used to hold a piece of textile fabric during the sewing, basting or ripping of the latter. Fig. 2 is an enlarged longitudinal section of the device as the same appears when removed from a table top or other support, and Fig. 3 is a horizontal section taken in the plane indicated by the line 3-3 of Fig. 2, looking downwardly.

Similar letters of reference designate corresponding parts in all of the views of the drawings.

Among other elements my novel work-holding device comprises a body A. This body A may be of any construction and material and may be fixed on a table top or other support in any manner compatible with the spirit of my invention without in-

volving a departure from the scope of my invention. I prefer, however, to make the said body of cast or other metal and in general U-form, and to provide it at the extremity of its arm a with a vertically-disposed, threaded aperture b, and at the extremity of its other and upper arm c with a needle holder d. I also prefer to employ a screw B for fixing the body A and the device as a whole with respect to a table top or other support. The said screw bears in the threaded aperture b of the lower arm a of the body, and is provided at its lower end with a flattened head e while its upper end is arranged to exert pressure against the underside of the table top after the manner shown in Fig. 1. From this it follows that when the body A is positioned as shown in Fig. 1, relative to a table top or the like, and the screw B is turned upwardly, the table top will be securely clamped between the upper end of the screw and the lower end of the needle holder d, with the result that there is no liability of the device being pulled or knocked off or changed in position on the table top. It will also be apparent that when it is desired to remove the device from the table top or change the position of the former on the latter, the same may be readily accomplished after the screw B is turned downwardly or loosened.

By reference to Figs. 2 and 3 of the drawings it will be observed that the needle holder d is provided with a vertical central tapering bore f which extends throughout its height, and that a needle C is placed and held in an upright position in the said bore, and when the holder is clamped in position for use, the needle is held rigidly in place due to the wedging action accomplished by the needle being forced upwardly in the tapering bore of the needle holder. The said needle C, which may be an ordinary sewing needle or a needle of any other approved type is removably arranged in the holder d and extends a considerable distance above the same and has its point uppermost as illustrated for a purpose presently set forth.

By virtue of the needle C being removably arranged in the holder d, a new needle may be easily and expeditiously substituted for one broken or otherwise impaired. It will also be observed that when desirable or necessary an ordinary pin may be substituted for the needle. In this connection I desire it distinctly understood that the term needle

as herein employed is intended to comprehend not only a pin but a pointed, pin-like device of any description appropriate to the function of the present device.

5 In using my novel device, the device is clamped on a table top or the like and the piece of fabric to be held is placed on the needle C as shown in Fig. 1. With this done the needle C will securely hold the piece of 10 fabric without liability of the same slipping or being casually released, and yet when it is desired to shift the piece of fabric the same may be readily lifted off the needle and replaced in a new position on the same. It 15 will also be apparent that the engagement of the needle C with the fabric does not in any manner injure the fabric, which is an important desideratum.

20 While the piece of textile material is held by my novel device, the seamstress is enabled to conveniently handle and sew, baste or rip the fabric, and this without the necessity of leaning over, sitting in a cramped position or being otherwise subjected to discomfort.

25 In addition to the advantages which I have hereinbefore ascribed to my novel work-holding device, the same is obviously simple and inexpensive in construction and yet is 30 adapted to enhance rather than detract from the neat appearance of a sewing table or the like.

Having described my invention, what I claim and desire to secure by Letters Patent, is:

35

1. A work-holder comprising a body having a rigid needle holder provided with a vertical tapering bore, means for fixing said body to a table-top or the like, and a needle removably arranged in and extending upward from said bore of the needle holder, and when in operative position the needle is held rigidly in place by being wedged in the tapering bore of said holder.

40

2. A work-holder comprising a U-shaped body adapted to straddle the edge of a table top or the like, and having a vertically disposed, threaded aperture at the extremity of its lower arm and a needle holder provided with a vertical central bore at the extremity 45 of its upper arm, a needle removably arranged in said bore of the needle holder and extending above the upper end of the same, and a screw bearing in the threaded aperture of the body and arranged to exert pressure 50 against the underside of a table top or the like.

55

In testimony whereof I affix my signature in presence of two witnesses.

ALICE E. BOOTH.
